UNITED STATES PATENT OFFICE.

HARRY JUTSUM HARTSHORN, OF HERNE BAY, ENGLAND.

DESIGN FOR A DISPLAY STAND FOR TOBACCO PIPES AND SMOKERS' ACCESSORIES.

Application filed February 24, 1925. Serial No. 12,468. Term of patent 14 years.

To all whom it may concern:

Be it known that I, HARRY JUTSUM HARTSHORN, a subject of the King of Great Britain, residing at 2 Avenue Road, Herne Bay, England, have invented a new, original, and ornamental Design for Display Stands for Tobacco Pipes and Smokers' Accessories, of which the following is a specification, reference being had to the accompanying drawing, forming part thereof.

The figure is a perspective view of a display stand for tobacco pipes and smokers' accessories showing my new design.

I claim:

The design for a display stand for tobacco pipes and smokers' accessories as shown.

HARRY JUTSUM HARTSHORN.
